CONTROL APPARATUS

Original Filed July 31, 1926 2 Sheets-Sheet 2

UNITED STATES PATENT OFFICE

HANS HENRIK CHRISTIAN GRONDAHL, OF CHICAGO, ILLINOIS, ASSIGNOR TO WESTERN ELECTRIC COMPANY, INCORPORATED, OF NEW YORK, N. Y., A CORPORATION OF NEW YORK

CONTROL APPARATUS

Original application filed July 31, 1926, Serial No. 126,167. Divided and this application filed May 4, 1928.
Serial No. 275,139.

This invention relates to control apparatus, and more particularly to an interlocking apparatus between a motor circuit switch and a clutch operating lever, and is a division of my Patent 1,691,058 of November 13, 1928.

5 The primary object of this invention is to provide a simple and efficient interlocking apparatus between a plurality of control means for a material treating apparatus.

10 In accordance with the general features of this invention as applied to a material treating apparatus, particularly to apparatus for conveying and quenching material for use in connection with the heat treatment thereof, there is provided an interlocking apparatus between a motor circuit switch and a clutch operating lever. Specifically, a hand wheel fixed to a screw projects a stop pin into the path of the lever to prevent the lever from being shifted until a hinged cover plate 15 of a switch housing is closed, the closing of which serves to open the motor circuit and also permits the lowering of a latch which was projected into the path of the hand wheel when the cover was opened, by a cam surface 20 upon the cover, for the purpose of closing the motor circuit. With the closure of the cover the stop pin can be retracted for the purpose of shifting the lever and during this 25 operation the cover cannot be opened to close the motor circuit due to the position of the hand wheel.

These and other objects of the invention will be more apparent from the following detailed description and in connection with the accompanying drawings, wherein

30 Fig. 1 is a side view of a material treating apparatus embodying the features of this invention;

35 Fig. 2 is an end view of the driving end of the apparatus shown in Fig. 1 disclosing an arrangement of the clutch mechanisms;

40 Fig. 3 is an enlarged view of the clutch control mechanisms as shown in Fig. 2;

45 Fig. 4 is a side view shown partly in section of the control mechanism disclosed in Fig. 3;

50 Fig. 5 is an enlarged fragmentary vertical longitudinal sectional view of Fig. 1;

55 Fig. 6 is a transverse vertical sectional

view of a pair of conveyor units taken on the line 6—6 of Fig. 5;

Fig. 7 is an enlarged detailed sectional view of the upper portion of the sprayer devices as shown in Fig. 6, and

Fig. 8 is a fragmentary detailed perspective view disclosing a stack of metallic sheets supported by a conveyor tray linked to a conveyor chain.

Referring now to the drawings wherein like numerals have been used to designate similar parts throughout the various figures, it will be observed that the material treating apparatus includes a plurality of conveyor units denoted generally by the numeral 10 comprising upright frames 11 which are mounted on the floor of a pit 12 which is provided with a screened covering or floor 14. The upper portions of the frames 11 extend upwardly through the screened floor 14 and at their upper ends support two pairs of oppositely disposed and spaced supports or channels 15. The innermost channels 15 support a pair of parallel, angular guides 16 (Fig. 6) which serve as a sliding support for a plurality of spaced inserts 18 which traverse and are secured to links 19 of conveyor chains 20. These conveyor chains 20 reach between sprockets 22 which are mounted on a shaft 23 at the driving end of the apparatus (Fig. 5) and sprockets 24 (Fig. 1) suitably mounted at the opposite end of the apparatus. Positioned medially of the frames 11 directly beneath the guides 16 are a pair of channel members 26 (Fig. 6) which function similarly to the guides 16 and serve to support the inserts 18 in the lower reach of the conveyor chain 20. It will be clear that the guides 16 and the channel members 26 serve to prevent sagging of the conveyor chain 20 and likewise serve to retain and guide the chain in its proper predetermined position.

85 The driving mechanism for the conveyor chain 20 includes an electric motor 27 (Fig. 5) which is suitably mounted within a pit 28 and forms a part of an electrical circuit 29 shown in Fig. 3. This motor 27 transmits power to a shaft 30 arranged in axial alignment with the motor shaft (Fig. 5) through the medium of suitable speed reduction 90 95 100

gears (not shown) and the shaft 30 is connected with a clutch shaft 31 by means of a sprocket chain 32. The clutch shaft is mounted at its ends in bearing members 34 (Fig. 2) within the pit 28 and revolubly mounted upon the shaft 31 adjacent each of the bearing members 34 is a sprocket 35. The sprockets 35 are operatively connected with the shaft 23 by means of suitable chains 38. These sprockets 35 are formed integral with a clutch member 36 which are adapted to be engaged by companion clutch members 37 keyed to and slidably mounted upon the shaft 31. Spaced upright bearing members 39 serve as additional bearing supports for the clutch shaft 31 and at their upper ends slidably support a shifter rod 40 which is connected at each end to the slidable clutch members 37 by means of suitable forked members 42 depending therefrom. The shifter rod 40 is adapted to be reciprocated by means of a vertically disposed control lever 43 which is pivoted at 45 within an upright control support 46 and is connected at its lower extremity with the shifter rod 40 by means of a link 47.

At the upper end of the control support 46 is a clutch control mechanism denoted generally by the numeral 49 (Figs. 2, 3, and 4). This clutch control mechanism 49 comprises a screw 50 threaded within a suitable bearing 51 provided at the upper extremity of the support 46. One end of the screw 50 terminates in a locking or stop pin 53 while the other end of the screw supports a hand wheel 54 secured thereto. When the hand wheel 54 is in the position shown in Fig. 4 with its inner face abutting the end of the bearing 51, the lock pin 53 of the screw 50 will project or lie within the path of the control lever 43. Thus when the lever is in its normal vertical or neutral position the stop pin 53 will project through an opening provided in the lever 43 and the lever cannot be shifted until the stop pin has been retracted. Likewise when the lever 43 occupies its shifted position, it cannot be moved until the stop pin is retracted out of the path of one or the other of oppositely disposed lugs 55 formed on the lever, the stop pin when in its advanced position lying adjacent the cooperating surface of the lug.

Immediately beneath the hand wheel 54 is a housing 56 which is suitably secured to the control support 46 and serves to enclose a conventional double push button electrical switch 57 which is connected within the circuit 29. A hinged cover plate 59 having a cam surface 60 provided at the upper end thereof is adapted to be swung into and out of covering relationship with respect to the face of the switch 57. A pin 61 carried by the cover 59 is adapted to engage the lower button of the switch 57 when said cover member is moved to its covering position as shown

in Figs. 2, 3, and 4. The engagement of the pin 61 with the lower button of the switch 57 which is in series with the electrical circuit 29 containing the motor 27 causes the opening of the circuit and in order to reclose the circuit the cover 59 must be swung open so as to render possible the manual operation of the upper button of the switch 57. Pivoted at the point 63 immediately above one corner of the cover 59 (Fig. 3) is a latch 64, the upper surface of which is curved so as to permit the hand wheel 54 to be moved outwardly away from the bearing member 51 when the latch is in its lowermost position. When the hand wheel 54 is in the position shown in Fig. 4 the latch 64 is free to be moved upwardly and thus when the cover 59 is swung outwardly by grasping a knob 65 provided thereon, the cam surface 60 will engage with the underside of the latch 64 and cause said latch to be urged upwardly. However, when the hand wheel is moved to a position superimposing the latch 64, it will be impossible to swing the cover 59 outwardly by reason of the engagement of its cam surface 60 with the latch 64. In this connection it is also to be observed that the cover 59 must be completely closed and the latch 64 completely lowered in order to permit the hand wheel 54 to retract the pin 53.

The use of the hand wheel 54 and the screw 50 for retracting the stop pin 53 from operative relation with the lever 43 when the latter is in one or the other of its operative positions, it will be apparent, serves to provide a time interval of sufficient duration after the opening of the motor circuit which will insure that the motor and parts driven thereby will have ceased operating by the time the stop pin has been retracted. The lever 43 can then be moved to effect the disengagement of the clutch member 37 with its companion driven clutch member 36 without injury to the operator or damage to the driving or clutch mechanisms which might occur by attempting to shift the lever 43 before all moving parts have come to a standstill.

From the foregoing it will be clear that by means of this control mechanism 49 the control lever 43 can never be operated while the motor 27 is functionally operative or in other words the control lever 43 can only be operated when the lock pin is in its retracted position. This condition can only exist when the cover 59 occupies the position shown in Figs. 3 and 4 and while it occupies this position the electrical source of power will be cut off. It will also be clear that the hand wheel 54 can never be rotated to withdraw the stop pin 53 when the cover 59 is swung away from the switch 57, in which position of the cover the upper button of the switch is accessible for closing the circuit. The latch 64 not only serves to prevent the actuation of the cover 59, but also serves to prevent the

outward movement of the hand wheel 54 when the cover is swung open. The importance of this construction will be more readily appreciated when it is understood that this apparatus is to be driven by a motor capable of starting under full load conditions without the use of compensators or other forms of electrical motor starting devices. For this reason it is necessary that some means be provided to prevent the actuation of the clutch mechanism while the motor is functionally operative.

In parallelism with the side of each conveyor unit 10 are quenching or spraying devices 67 which comprise horizontal pipes 68 having a plurality of perforations 69 (Fig. 7) formed therein. These pipes 68 are slidably mounted at spaced intervals by means of vertical guide supports 71 and are provided with an intake coupling 72 which is connected with a suitable source of water supply (not shown) by means of a suitable valve 73 (Fig. 5). The pipes 68 may be readily raised and lowered by the manipulation of a crank 75, which when rotated, operates capstans 76. These capstans 76 are connected with the lower ends of the supports 71 by means of suitable cables 77 which pass over pulleys 79 mounted at the side of the conveyor units 10. To facilitate the raising of the pipes 68 counterweights 80 are provided which tend to rotate the pulleys 79 over which the cables 77 pass. From the disclosure it will be apparent that the operation of the crank 79 will cause the raising or lowering of two sets of spraying devices 67. Excess water or other quenching medium passes from the pit 12 through a drain 80 (Fig. 5).

In the operation of the treating apparatus provided with the control and interlocking apparatus, hereinbefore described, material such as metallic sheets 81 as shown in Fig. 8 stacked upon a suitable conveyor tray 83 when positioned within an annealing furnace 84, may be coupled with one of the links of the conveyor chain 20 by means of a suitable detachable connecting member 86. The hand wheel 54 is rotated so as to retract the lock pin 53 from the opening in the lever 43 as shown in Figs. 3 and 4, and the control lever 43 is actuated in one direction or the other so as to effect the engagement of one of the clutch members 37 with its companion driven clutch member 36. At this point it is to be understood that each of the combined clutch members 36 and 37 serves to independently operate two conveyor units 10. The hand wheel can then be operated to carry the lock pin 53 into its projected position again where it will lie in the path of one or the other of the lugs 55 formed on the lever 43. The control lever 43 will thus be positively prevented from being returned to its neutral position or to its other operative position. The cover

59 can now be opened and the upper starting button of the switch 57 actuated to close the circuit 29 including the motor 27. The sheets 81 are advanced from the furnace along the upper surfaces of the supporting channels 15 toward the driving end of the apparatus. The motor is stopped when the sheets have been carried to their proper advanced position for the quenching operation, by closing the cover 59 which as hereinbefore described serves to open the circuit to the motor and causes the latch 64 to be lowered from the path of the hand wheel 54. Thereafter the latter may be operated to retract the stop pin 53 and the lever 43 is then free to be shifted.

What is claimed is:

1. In a material handling apparatus, material handling means, an electrical circuit containing a motor for driving the handling means, a clutch mechanism connecting the motor and the handling means, a lever for controlling the clutch mechanism, a stop member movable into engagement with the lever for maintaining it in a predetermined position, a switch for opening and closing the motor circuit, and means operatively associated with the stop member and the switch for preventing the operation of the switch to close the motor circuit while the stop is in an inoperative position.

2. In a material handling apparatus, material handling means, an electrical circuit containing a motor for driving the handling means, a clutch mechanism connecting the motor and the handling means, a lever for controlling the clutch mechanism, a reciprocal stop member for maintaining the lever in an operative position, a switch for opening and closing the motor circuit, means for retracting the stop member from the lever, and means operatively associated with the stop member retracting means and the switch for preventing the operation of the switch to close the motor circuit while the stop is in an inoperative position.

3. In material handling apparatus, material handling means, an electrical circuit containing a motor for driving the handling means, a clutch mechanism connecting the motor and the handling means, a lever for controlling the clutch mechanism, a stop member operatively associated with the lever for maintaining it in a predetermined position, a switch having operating elements for opening and closing the motor circuit, a pivotal plate for covering and uncovering the operating face of the switch and serving to operate the circuit opening element thereof when moved to its covering position, and means operatively associated with the plate and the stop member for preventing an operation of the stop member to free the lever while the plate is in an uncovering position for the purpose of closing the motor circuit.

4. In a material handling apparatus, material handling means, an electrical circuit containing a motor for driving the handling means, a clutch mechanism connecting the motor and the handling means, a lever for actuating the clutch mechanism, a stop member for maintaining the lever in a predetermined position, a screw for advancing and retracting the stop member to and from operative relation with the lever, a hand wheel for operating the screw, a switch for opening and closing the motor circuit, a plurality of cooperating pivotal members operatively associated with the hand wheel, and the switch for positively preventing the operation of the hand wheel to retract the stop member from the lever while the motor circuit is closed and when the stop member is in a retracted position positively preventing the closing of the motor circuit. 70
5. In a material handling apparatus, material handling means, an electrical circuit containing a motor for driving the handling means, a clutch mechanism connecting the motor and the handling means, a switch for opening and closing the motor circuit, individual controlling means for the switch and the clutch mechanism, and interlocking means including a simultaneously rotatable and reciprocable element operatively associated with the individual controlling means for limiting the actuation of the latter means to a predetermined sequence. 75
6. In a material handling apparatus, material handling means, an electrical circuit containing a motor for driving the handling means, a clutch mechanism connecting the motor and the handling means; a switch for opening and closing the motor circuit, individual controlling means for the switch and the clutch mechanism, and interlocking pivotal and reciprocable means operatively associated with the individual controlling means for rendering the controlling means for the clutch mechanism inoperative while the controlling means for the switch is in a position to permit the operation of the switch to close the motor circuit. 80
7. In a material treating apparatus, material conveying means, driving means for the conveying means including a source of power, means for connecting the source of power with the driving means, means for operatively and inoperatively connecting the driving means with the conveying means, means for controlling the connecting means, and means for rendering the controlling means inoperative while the means for connecting the source of power with the driving means is accessible for operation. 85
8. In a material handling apparatus, material handling means, an electrical circuit containing a motor for driving the handling means, means for operatively and inoperatively connecting the driving means with the
- handling means, a switch for opening and closing the motor circuit, individual controlling means for the switch and the connecting means, the switch controlling means provided with a cam surface, and movable means arranged between the respective controlling means and actuated by the said cam surface for rendering the controlling means for the connecting means inoperative while the controlling means for the switch is in a position to permit the operation of the switch to close the motor circuit. 90
9. In a material handling apparatus, material handling means, an electrical circuit containing a motor for driving the handling means, a clutch mechanism connecting the motor and the handling means, a switch for opening and closing the motor circuit, individual controlling means for the switch and the clutch mechanism, the switch controlling means provided with a cam surface, and pivotal means arranged between the respective controlling means and movable into the path of the controlling means for the clutch mechanism by said cam surface when the switch controlling means is moved to permit the operation of the switch to close the motor circuit. 95
